Murray Kellerman, Brooklyn, N. Y.

Application February 28, 1945, Serial No. 118,176

Term of patent 3½ years

(Cl. D34—15)

To all whom it may concern:

Be it known that I, Murray Kellerman, a citizen of the United States, residing at Brooklyn, in the county of Kings and State of New York, have invented a new, original, and ornamental Design for a Toy Musical Merry-Go-Round, of which the following is a specification, reference being had to the accompanying drawing, forming part thereof.

I claim:

The ornamental design for a toy musical merry-go-round, as shown.

MURRAY KELLERMAN.
